UNITED STATES PATENT OFFICE.

JOHN KENSLER, OF BUFFALO, NEW YORK.

IMPROVEMENT IN CAR-COUPINGS.

Specification forming part of Letters Patent No. 171,730, dated January 4, 1876; application filed October 6, 1875.

To all whom it may concern:

Be it known that I, JOHN KENSLER, of Buffalo, in the county of Erie and State of New York, have invented a Car-Coupling; and I do hereby declare that the following is a full, clear, and exact specification, wherein are set forth the nature and particulars of my invention, and the mode in which it is carried into effect, and its novel features pointed out in the claims.

In describing this invention I shall refer to the accompanying drawings making a part of this specification, and illustrating my invention more fully.

In the same, Figure 1 is a bottom view of a car having my coupling shown in a longitudinal horizontal section. Fig. 2 is a longitudinal vertical section, and Fig. 3 an end view, of the car illustrating the uncoupling apparatus.

Like letters of reference in the several figures indicate corresponding parts wherever they appear.

A is a hollow draw-head of a car-coupling. It is movably attached to the car-body or platform by a bracket, B, and the bolt C passing through the draw-bar and bracket. This bracket B is fixed to the platform by the shank B' and screw-nut B'', as clearly indicated in Fig. 2, and it is provided with a slot-hole, B''', of suitable length, for the passage of the before-mentioned bolt C. E is a coupling-hook pivoted at F within the draw-head A, and projecting out of the same a sufficient distance to allow the proper engagement of the said hook. It has a barbed end, G, beveled on its point to readily engage with the draw-head of the opposite coupling. A spring, H, is attached to this hook near its center of motion, bearing with its free end against the inner wall of the draw-head A. I is a spring attached to the lower side of the draw-head, and bearing upon a transverse plate, I'. It serves to keep the draw-head elevated, and in proper position. K is an iron chair containing the spring arrangement of the draw-head, consisting of the spring-bar L, having a head, L', and the coiled or other spring N, operating between the brackets O O', in such manner that one end of the spring N bears against the bracket O, and the other end against a shoulder on the spring-bar L, as clearly shown in Fig. 1.

The draw-head A rests against the spring-bar L, and when cars are coupled will recede with the said spring-bar, where the spring or cushion N deadens the blow to destroy its effect upon the cars.

So far as the parts now described are concerned, they relate to the coupling of cars automatically, and to uncouple them the device is resorted to consisting, as shown in Figs. 1 and 3, of the hand-lever P, properly pivoted at Q on one side of the platform, and connected with the pivoted hook E by the connecting-rod R and the stud R', said stud being movably attached to the rod R with one end, and passing through the wall of the draw-head A opposite the barbed head of the draw-bar E, permanently connecting therewith with its other end. A hand-rod, S, traversing the platform, is also attached to the lever P at T, and passes through the guide U to the opposite side of the platform.

The operation of this coupling will be readily understood. Duplicates of the device described are placed centrally on each end of a car, so that whenever two cars meet the hooks E will engage with each other, and thus connect the several cars. This operation is obvious, and need not be more particularly described, attention being simply called to the spring H, which tends to keep the hooks engaged.

In order to uncouple cars, it will be seen that on each side of the platforms there is one lever, P, and one hand-rod, S, which, if one be pushed away from and the other pulled toward the operator, will disengage both hooks, so that the cars are separated, and can be removed at pleasure. If desired, a stop arrangement may be placed on lever P to lock it in its various positions, so as to prevent accidental uncoupling, &c.

The device described has several advantages over hook-couplings as now in use, which may be indicated as follows: It is adapted for cars of different heights, and will readily engage them on account of the pivoted draw-head A, which is capable of a vertical movement within the guide-timbers, so that when cars of different heights are coupled, the draw-head of the lower car will depress that of the higher one by means of the beveled hooks,

and the enlarged mouth of the draw-bars, and thus make certain connection. The application of the spring I is optional, since the same result, *i. e.*, coupling cars of varying heights may be obtained by letting the draw-bar A rest upon the transverse plate I', and the higher car taking it up, or raising it to make the connection. Pivoting the hook E within the draw-head in a manner to swing in a horizontal plane, and so pivoting the draw-bar A as to allow a vertical movement thereof, insures a better and prompter coupling, and is safer, since the coupling will follow the undulatory motion of the moving cars. The cars can be automatically coupled, and may be uncoupled without compelling the operator to step between them, and thus hazard life and limbs.

Having thus fully described my invention, so as to enable others skilled in the art to which it pertains to make and use the same, I desire to secure to me by Letters Patent of the United States:

1. In a car-coupling, the hollow draw-head and bumper A pivoted within the slot B''' of the depending bracket B, with capability of a combined lateral and vertical movement, in combination with the barbed coupling-bar E, pivoted within said draw-head (by the transverse bolt F) with capability of a horizontal

motion, and projecting with its barbed head only out of said draw-head, substantially as described, for the purpose set forth.

2. The hollow draw-head and buffer A, in combination with the hook E, provided with the spring H, and pivoted within said draw-head by the transverse bolt F, said draw-head A being pivoted to the depending bracket B by the bolt C, and the hook operated by the connecting-rods R R', lever P, and hand-rod S, the whole when constructed and arranged, substantially as described, for the use and purpose set forth.

3. The combination, with the draw-head A, provided with the barbed coupling-bar E in its interior, of the stud R', passing through the wall opposite the barbed head, connecting-rod R, pivoted lever P, hand-rod S, and connecting with the said lever P at T, and the guide U, all being constructed as described.

In testimony that I claim the foregoing as my invention I have hereto set my hand and affixed my seal this 27th day of September, A. D. 1875, in the presence of two subscribing witnesses.

JOHN KENSLER. [L. S.]
